FURNITURE STRUCTURE

Max Koenigsberg, Highland Park, Ill., assignor to The Englander Company, Inc., Chicago, Ill., a corporation of Delaware

Application October 5, 1954, Serial No. 460,356

2 Claims. (Cl. 155—180)

The present application relates to a novel furniture structure and more particularly to a novel combination including a frame member, an exterior covering fabric, a dust cover, and securing means adapted for use in chairs, divans, beds, vehicle seats, and the like.

In the past, furniture structures of the type contemplated herein have usually included wooden frame members, so that covering fabrics could be stapled, tacked, or otherwise easily secured thereto. The present invention contemplates the use of metal frame members, and has for a primary object the provision of a novel structure wherein an outer covering fabric and a fabric dust cover are secured to the metal frame in a simple and economical manner.

A further object of the present invention is to provide a novel structure of the above described type wherein the fabrics are secured to the metal frame member in a manner which substantially eliminates any possibility of tearing the fabrics.

Still another object of the present invention is to provide a novel structure of the above described type wherein an outer covering fabric is secured to a metal frame member in a manner so that the fabric is drawn tight to provide a pleasing, smooth appearance.

Other objects and advantages of the present invention will become apparent from the following description and the drawings, wherein:

Fig. 1 is a fragmentary cross-sectional view of a chair, divan, day-bed, or other similar piece of furniture, embodying the novel structure of this invention;

Fig. 2 is an enlarged fragmentary perspective view showing the novel structure of this invention partially assembled;

Fig. 3 is a fragmentary cross-sectional view showing the novel structure of this invention in further assembled relationship;

Fig. 4 is an enlarged fragmentary cross-sectional view similar to Fig. 3, but showing the novel structure of this invention fully assembled;

Fig. 5 is a fragmentary perspective view of a modified form of the metal frame member which may be used in the structure of this invention;

Fig. 6 is a cross-sectional view showing another modified form of the present invention in partially assembled condition; and

Fig. 7 is a fragmentary cross-sectional view showing the structure of Fig. 6 in its fully assembled condition.

Referring now more specifically to the drawings, where-in like parts are designated by the same numerals throughout the various figures, a piece of furniture 10 incorporating the novel structure of the present invention is shown in Fig. 1. This piece of furniture includes a metal frame 12, which may form a part of a box-spring unit including coil-springs 14. An outer covering fabric 16 is disposed over the springs and the frame, and a dust cover 18 is provided for closing the bottom of the frame. The outer cover and the dust cover are secured to the

2

frame in a manner which will be described below. The frame is supported by any suitable means such as a plurality of legs 20 of which only one is shown, and a cushion or mattress 22 is usually disposed on top of the box-spring unit.

The novel structure of the present invention is more clearly shown in Figs. 2, 3, and 4 and includes a sheet metal frame member 24 which forms a part of the above described frame 12. The frame member 24 is provided with a generally vertical web 26, which may have a central inwardly formed channel portion 28 to add strength and rigidity thereto. In addition, a flange 30 extends inwardly from the bottom edge of the web, and a similar horizontal flange 32 extends inwardly from the upper edge of the web.

In accordance with the present invention, the outer fabric cover 16 and the fabric dust cover 18 are secured to the frame member by means of a plurality of pointed barbs or tabs 34 struck downwardly from the lower flange 30. As shown in Fig. 2, the barbs or tabs are initially formed so that they are inclined downwardly and outwardly with respect to the flange in order to retain the dust cover which is first applied thereto and stretched between opposite sides of the frame. A marginal portion 36 of the fabric cover 16 is then pressed onto the tabs or barbs. It is important to note that this marginal portion is doubled over and stitched as at 38 to provide a hem, and that an elongated wire 40 extends for the length of the hem and is retained between the thicknesses thereof.

After the marginal portion or hem of the fabric 16 is pressed onto the tabs, the tabs are folded rearwardly or inwardly of the frame through the position shown in Fig. 3 to the position shown in Fig. 4. It will be appreciated that during and after this folding operation, the hem of the outer fabric 16 serves to prevent disassembly of the dust cover from the tabs. It should also be noted that, as the tabs 34 are folded to the position shown in Fig. 4, the outer fabric 16 will be stretched so that it will have a smooth appearance. During such stretching, the double thickness of the hem serves to reduce any possibility of tearing of the fabric, and the wire 40 substantially eliminates any possibility of injury to the fabric since it serves to spread the stresses applied to the fabric by the tabs or barbs. As shown in Fig. 4, the tabs 34 are preferably folded, so that the wire 40 and the portion of the hem surrounding it are firmly pressed or clamped against the dust cover 18 as at 42. Thus, the dust cover is gripped between the wire and the flange 30, so that any tension forces applied to the dust cover will be resisted by this gripping action and any possibility of the dust cover tearing on the tabs or barbs is reduced.

In Fig. 5 there is shown a slightly modified sheet metal frame member 44, which may be used in place of the above described frame member 24. The frame member 44 is identical with the frame member 24, except that it is provided with barbs or tabs 46 which are struck from a bottom flange 48 so that their points normally extend inwardly of the frame member rather than outwardly. However, the tabs 48 are preferably bent in the manner shown in Fig. 5, so that before the application of the fabric covers thereto they extend downwardly and outwardly. Thus, the fabric covers may be applied to the tabs 46 in substantially the same manner as they are applied to the tabs 34.

Figs. 6 and 7 disclose another form of the present invention which is substantially identical to the embodiment shown in Figs. 2 through 4, except for the modified shape of barbs or tabs 50 which replace the above

described tabs 34. More specifically, each barb 50 is initially formed so that it has a base portion 52 extending downwardly and outwardly, and an outer end portion 54 which extends substantially vertically downwardly or even downwardly and slightly inwardly of the frame. With this structure, the dust cover may be applied to the barbs and initially retained in assembled relationship therewith by the outwardly inclined portions 52 in the same manner that the dust cover is applied and initially retained by the barbs or tabs 34. It will be appreciated, that since the tabs 34 are inclined outwardly, there is a possibility that the cover fabric 16 may accidentally slip therefrom before they are bent rearwardly and while the workman's attention is directed toward pressing the fabric on other tabs. This problem is substantially eliminated by the structure shown in Figs. 6 and 7, since the cover fabric may be slightly stretched before it is applied to the downwardly extending end portions 54 of the tabs, and the tension in the fabric will prevent it from becoming disassembled from the tabs before the workman has had an opportunity to fold the tabs to their final position shown in Fig. 7.

From the above description it is seen that the present invention has provided a novel structure wherein a plurality of pieces of fabric may be effectively secured to a metal frame member in a simple and economical manner. In addition, it is seen that the present invention has provided a novel structure wherein the pieces of fabric may be secured to a metal frame member by means of integral tabs without danger of injuring or tearing the fabric.

While the preferred embodiments of the present invention have been shown and described herein, it is obvious that many structural details may be changed without departing from the spirit and scope of the appended claims.

The invention is claimed as follows:

1. A furniture structure of the type described comprising a sheet metal frame member having an elongated substantially flat portion, said frame member including a plurality of spaced integral tabs struck from and respectively leaving an opening in said flat portion and initially inclined downwardly and outwardly from integral junctions with said flat portion of said frame member, a fabric dust cover impaled on said tabs and extending in

a direction away from a side of said junction opposite from said openings, a fabric piece covering said frame member and having a double thickness hem impaled on said tabs over said dust cover, said fabric piece extending oppositely from said dust cover, and an elongated wire extending longitudinally through said hem between the thicknesses thereof for spreading any stresses applied to the fabric piece by said tabs, at least end portions of said tabs being folded inwardly of said frame member to sides of said junctions opposite from said openings and toward said frame member portion for stretching said fabric piece and for clamping said hem and said wire against said dust cover, so that the dust cover is gripped between the wire and said frame member portion.

2. A furniture structure of the type described comprising a sheet metal frame member having an elongated substantially flat portion, said frame member including a plurality of spaced integral tabs struck from said flat portion thereof so as to leave openings in said portion, each of said tabs including a base portion extending from an integral junction with said portion downwardly and outwardly with respect to said frame member and over its associated opening, and an end portion extending substantially downwardly with respect to said frame member and at an angle to said base portion, a fabric dust cover impaled on said tabs and extending in a direction away from said openings and retained by said tab base portions, a fabric piece covering said frame and having a hem impaled on said tab end portions over said dust cover, said fabric piece extending oppositely from said dust cover, and an elongated wire extending longitudinally through said hem for spreading any stresses applied to the fabric means by said tabs, said tab end portions being folded inwardly of said frame member to sides of said integral junctions opposite from said openings and toward said frame member portion for trapping said hem and said wire.
